UNITED STATES PATENT OFFICE

132,780

DESIGN FOR A WALL BRACKET LAMP

Herman Edward Jumper, Tiffin, Ohio

Application January 3, 1942, Serial No. 105,009

Term of patent 7 years

To all whom it may concern:

Be it known that I, Herman Edward Jumper, a citizen of the United States, residing at Tiffin, in the county of Seneca and State of Ohio, have invented a new, original, and ornamental Design for a Wall Bracket Lamp, of which the following is a specification, reference being had to the accompanying drawing, forming part thereof.

I claim:

The ornamental design for a wall bracket lamp, as shown.

HERMAN EDWARD JUMPER.
